UNITED STATES PATENT OFFICE.

GEORGE BERNHARDT DAMON, OF GLENSIDE, PENNSYLVANIA, ASSIGNOR, BY MESNE ASSIGNMENTS, TO LEHIGH COAL & NAVIGATION CO.

APPARATUS FOR SEPARATING FINE COAL AND THE WASTE MATERIALS THEREOF.

1,072,833.

Specification of Letters Patent.

Patented Sept. 9, 1913.

Application filed August 8, 1908. Serial No. 447,630.

To all whom it may concern:

Be it known that I, GEORGE B. DAMON, of Glenside, in the county of Montgomery, and in the State of Pennsylvania, have invented a certain new and useful Improvement 5 in Apparatus for Separating Fine Coal and the Waste Materials Thereof, and do hereby declare that the following is a full, clear, and exact description thereof.

10 The object of my invention has been to provide an apparatus for reducing the percentage of incombustible material in fine anthracite and bituminous coal, and anthracite and bituminous waste materials, assorting 15 their particles as to size, and separating the dust therefrom, and especially for reducing the percentage of incombustible material in culm, and more particularly such an apparatus which shall be capable of operating 20 upon the materials in a dry condition; and to such ends my invention consists in the apparatus of separating fine anthracite and bituminous coal, and anthracite and bituminous waste materials, hereinafter 25 specified.

By "fine" anthracite coal, I mean coal of a size not substantially larger than "buckwheat," and by "fine" bituminous coal, I mean coal of a size not larger than "buckwheat" 30 in anthracite coal.

In the accompanying drawings Figure 1 is a vertical longitudinal sectional view of one embodiment of my invention, and Fig. 2 is a vertical transverse sectional view taken 35 on the line 2-2, Fig. 1.

In the production of anthracite coal, the coal is mined in as large lumps as possible, and is then passed through a breaker to break it up into smaller sizes. This results 40 in the production of a considerable percentage of coal that is too small for satisfactory sale because of the competition of bituminous coal. By my apparatus, the particles of this coal (crushed down to a suitable size, if necessary) can be assorted as to size; its dust 45 can be removed, and the percentage of incombustible material can be reduced, if necessary, so that the useful material will be put into form suitable for briquetting. The mining of anthracite coal also results in the production of a large amount of material containing dust and coal too small for satisfactory combustion by the ordinary processes. This material is known as "culm." 50 Culm is too high in incombustible material

for satisfactory combustion by the ordinary apparatus. It is also too fine to burn satisfactorily on a grate. I desire by my apparatus to separate incombustible material of the culm so that the portions thereof which 55 are suitable may be made into briquets, which shall burn substantially as well as the domestic sizes of coal.

In order to produce satisfactory briquets from culm, it is not only necessary that the 60 percentage of incombustible material should be reduced, but that the particles below a certain size should be removed, because the amount of pitch necessary to bind the particles into a briquet is proportionately larger 65 for small particles than for large particles, as the amount of pitch necessary to coat a small particle is proportionately larger than that to coat a large particle. Pitch is expensive, and it is therefore not economical 70 to make briquets of particles that are too fine. Therefore, another object of my invention has been to provide an apparatus to remove the dust which is too fine for use 75 in briquets.

It is also desirable that the particles of a briquet shall be of substantially uniform size, because this is necessary to secure satisfactory combustion of the briquet under ordinary circumstances. The larger particles will burn more slowly than the smaller particles, if the particles be of different sizes. Therefore, the combustion will progress 80 from the outer surface of the briquet toward the center in an uneven manner, and this uneven combustion will ordinarily result in smoke. If the particles are of substantially uniform size, the combustion will progress 85 evenly, and there will be a minimum of smoke. Therefore, an object of my invention has been to provide an apparatus to so assort the particles that the briquets may be made of particles of substantially uniform 90 size.

In the production of bituminous coal, 100 there is much material that is so small that it cannot be satisfactorily gasified when burned on a grate, and there is waste material which is undesirably high in incombustibles. There is also much bituminous coal 105 with an undesirably high percentage of sulfur and pyrites, especially when used for metallurgical purposes. By means of my apparatus the fine material can be prepared for briquetting, and the percentage of in- 110

combustibles and of sulfur and pyrites can be reduced. The percentage of sulfur and pyrites in bituminous coal of any size can be reduced by crushing it down, if necessary, 5 and passing it through my apparatus.

While my apparatus is capable of working upon all the before stated materials, I have chosen to illustrate it by its application to culm, because in such application its advantages most completely appear. 10

My apparatus is capable of embodiment in many different forms, and the apparatus illustrated is to be taken as merely illustrative of one of many forms in which it may 15 be embodied.

It has heretofore been believed that the dust in culm was largely pure coal. I have discovered that, contrary to previous belief, the finer dust in culm is higher in percentage 20 of incombustible material. This I believe to be due to the fact that in being mined, washed and assorted, the coal is coated by incombustible materials coming from the strata confining the vein of coal, and that a 25 small particle will hold a larger percentage of such material on its surface than would a larger particle. I have also discovered that by means of a current of air acting under certain conditions on a stream of falling 30 culm, I can separate this fine comparatively incombustible material from the larger more useful material, and can also assort the larger material to great advantage. My apparatus is based on these discoveries.

As before stated, my apparatus can be embodied in many different forms, and I have chosen to illustrate two of such embodiments which I have found advantageous. 35

That form of apparatus illustrated in Figs. 1 and 2 comprises a framework supporting, above, rollers 10 and 11, over which runs a belt 12, upon which the culm is deposited in any desired manner. The upper 40 surface of the belt runs toward the left in Fig. 1, or in the direction which I shall term "forward." Beneath the roller 10 and in position to catch the falling culm is a hopper 13, said hopper comprising parallel 45 vertical sides and inclined bottoms 14 and 15. The inclined bottom 15 stands a little above the bottom 14 so that the culm may slide down the bottom 14 and beneath the bottom 15. The culm thus falls off of the 50 lower end of the bottom 14 in a uniform stream. The lower end of the bottom 14 extends into a closed chamber having a width approximately equal to that of the bottom 14, the side walls 16 and 17 of the 55 chamber being parallel and the said chamber having a length and height which may conveniently be approximately equal. The chamber is closed by a front wall 18 and a rear wall 19. The bottom of the chamber is 60 closed by three bins 20, 21 and 22 respec- 65

tively, which bins together occupy the entire bottom. Each bin is closed by a "hopper bottom" having in it a sliding door 23, and which door has beneath it a belt 24 that is adapted to carry away the material falling 70 through the door. Over the divisional wall between the bins 21 and 22, I preferably arrange a movable rider 25. This rider or guard has forwardly and rearwardly inclined upper faces meeting at an apex, and 75 it can be shifted over a division wall between the bins, forward or back, within the limits of its base, (which is in effect shifting the division wall between the bins) so as to exactly divide the material which is to go 80 into the respective bins. In the front wall 18 is an opening 26 that is preferably well up toward the level of the lower end of the bottom 14. In the rear wall 19 is an opening 27 whose area is larger than that of the opening 26 in the front wall. I find good 85 results to be obtained by making the rear openings approximately twice the area of the front opening. The height of the rear opening is determined by special conditions, 90 which will be stated later in describing the operation of the apparatus. At the rear of the wall 19 is a partition 28, which, starting at its foot near the partition 19, preferably extends upward and rearward at an inclina- 95 tion to form a hopper-like bottom, the space between the said partition and the said wall being closed by the side walls 16 and 17 and by the roof 16^a. An opening 30 is formed in the partition 28 approximately opposite 100 the opening 27, and a suction fan 31, or other form of suction apparatus, is connected with said opening to exhaust air from the space inclosed, and thus to draw air through the opening 27. Any form of suction device 105 can be used.

In the separation of culm by means of the apparatus illustrated in Figs. 1 and 2, the culm (which has been dried if necessary) is deposited on the apron and allowed to fall 110 into the hopper. The opening between the bottom 15 and the bottom 14 is adjusted to permit a stream to pass, of sufficient quantity to make rapid operation possible, but not of sufficient thickness to prevent advantageous action of the air. The suction apparatus being in operation, a strong current of air enters through the opening 26 and strikes the falling stream of culm, causing the particles to fall at greater or less distances rearward of the vertical, according to the size, shape and weight of the particles. The bony coal, pyrites and large particles of coal fall into the bin 20. The briquetting material, which is high in carbon and not 115 too fine, falls into the bin 21, and the dust and material which is too fine for briquetting and which contains incombustible material in the shape of powder falls into the bin 22.

The various factors influencing the opera- 130

tion of my apparatus may be stated as follows:—The suction causes the air to pass in substantially straight lines from the opening 26 to the opening 27, and an accurate separation of the material, according to the size, shape and specific gravity, is effected. I have found that if a blast be forced through the opening 26 instead of a suction drawn through the opening 27, great confusion will 10 occur within the chamber, and efficient separation will not take place. The velocity of the air is adjusted to the size of the coal being treated; the larger the coal, the higher the velocity. If the velocity of the air is 15 too low, it does not sufficiently spread the material. The velocity should also be regulated according to the temperature to obtain the best results. If the culm has incombustible material in comparatively large 20 pieces, the front rider is moved somewhat to the rear. If the incombustible material, in the shape of impalpable powder, is present to an unusual degree, the rear rider is moved forward. If a high velocity of the 25 air is required, both riders will be moved rearward, and vice versa. I find it advantageous to place the opening 26 well up toward the level of the bottom 14, because the air in this position strikes the material before it has acquired much velocity, and therefore the material is subjected to the action of the stream of air for a longer time than it would be if the opening were lower down. This is of importance, because I 30 find that if the front opening be made too large, a good separation of the coal and ash is not effected. I find the best results to be obtained by making the rear opening larger than the front opening. I also find it is ad- 35 vantageous to locate the rear opening higher or lower according to particular conditions. A certain amount of the incombustible dust can be carried through the rear opening into the chamber in the rear. If the open- 40 ing be too high, the dust does not pass through it as well as if it be lower. I have also found that if the coal be flaky, it is more easily carried by the air, and it is then an advantage to have the rear opening high,

whereas if the coal be granular, it is with 50 much more difficulty carried by the air, and it is more advantageous to have the rear opening low. A door into the rear chamber of any convenient sort is provided, so that the dust may be removed therefrom. 55

While I have indicated the conditions to obtain the best results, a fair result can be obtained, notwithstanding many of such conditions are not observed. It will thus be seen that the agents controlling the va- 60 rious conditions are the cross sections and locations of the front and rear openings relative to the falling stream of culm to each other and to the bins, the velocity of the air and the location of the riders. 65

It is obvious that various changes can be made in the above-illustrated constructions which will be within the scope of my invention, and I desire not to be limited beyond the requirements of the prior art and 70 the necessary intendment of my claim. For instance, in the construction of Figs. 1 and 2, the suction fan can be directly connected with the opening 27, and the partition 28 omitted. 75

I claim:

An apparatus for separating fine coal and the waste materials thereof, including the combination of a closed chamber having substantially parallel side walls, said chamber being longer than its width, means for causing the materials to fall in a substantially uniform stream near one of the end walls of such chamber, said wall having an opening therein near the top of said stream, 80 the opposite end wall having a larger opening at a lower level, means for exhausting air through said last mentioned opening, and bins forming the bottom of said chamber, said bins being separated by walls 85 transverse to the length of said chamber. 90

In testimony that I claim the foregoing I have hereunto set my hand.

GEORGE BERNHARDT DAMON.
